UNITED STATES PATENT OFFICE.

WILLIAM S. FRIEDLANDER, OF PASSAIC, NEW JERSEY, ASSIGNOR TO
JACOB S. BERNHEIMER & BROTHER, OF NEW YORK, N. Y.

DESIGN FOR FABRIC.

SPECIFICATION forming part of Design No. 22,800, dated September 26, 1893.

Application filed May 27, 1893. Serial No. 475,794. Term of patent 3½ years.

To all whom it may concern:

Be it known that I, WILLIAM S. FRIEDLANDER, a citizen of the United States, residing at Passaic, in the county of Passaic and State of New Jersey, have invented and produced a new and original Design for the Decoration of Fabric, of which the following is a specification, reference being had to the accompanying drawing, forming a part thereof, which represents a plan view of a piece of fabric decorated in accordance with my design.

The leading, or characteristic, feature of the design consists of the representation of a

fox skin, in an outstretched position, including the head, legs and brush, such representation being placed upon the back ground with the mat effect produced by shadowy lines *a*, *a*, which appear at the marginal portions of the skin, producing a relief effect thereupon.

I claim—

The design for a fabric substantially as shown and described.

WILLIAM S. FRIEDLANDER.
